UNITED STATES PATENT OFFICE.

JOHN FRANCIS BOWDITCH, OF REVERE, MASSACHUSETTS.

PAINT-BRUSH.

SPECIFICATION forming part of Letters Patent No. 298,166, dated May 6, 1884.

Application filed January 18, 1884. (Model.)

To all whom it may concern:

Be it known that I, JOHN FRANCIS BOWDITCH, of Revere, in the county of Suffolk, of the Commonwealth of Massachusetts, have invented a new and useful Improvement in Paint-Brushes; and I do hereby declare the same to be described in the following specification, and represented in the accompanying drawings, of which—

10 Figure 1 is a side view of the brush; Fig. 2, a top view; Fig. 3, a section taken transversely of the ferrule; Fig. 4, a perspective view of the handle, cap, and tongue; Fig. 5, a section taken longitudinally of the ferrule.
15 In the annexed drawings, the letter A represents the handle; B, the bristles; C, the cap, and D the ferrule. In putting these together a hole is cut in a block of wood, afterward cap C and the handle A are driven through
20 such hole from the under side of the block and made fast in the latter. The block is then cut lengthwise on each side, underneath, forming a tongue, *a*, having the flat or straight sides *b* and the wedge-shaped point *a'*, such
25 tongue being thus formed of the lower end of the handle and the ends of the block on each side of such lower end. The bristles B are bunched in a mass, and the ends to be inserted
30 in the ferrule are provided with cement and then inserted in the ferrule D. The wedges
35 E E are then placed inside of the sides of the ferrule at the bottom, alongside of the mass of the bristles. These wedges are inserted with their thin edges *e* up into the ferrule along-
40 side of the butt-ends of the bristles and their thicker edges *e'* below, as shown in Fig. 3. The handle A, with the cap C, is then forced down into the ferrule from the top, the tongue *a* entering the mass of bristles, the wedge-
45 shaped point facilitating such entrance. As the tongue *a* enters among the bristles, it pushes them into two parts against the sides

of the ferrule D and the wedges E E. As the space between the thicker or lower edges of the wedges is smaller than that above the 45 wedges or under the cap, the two portions of the bristles thus jammed by the tongue *a* are forced into two dovetailed portions, and will successfully resist any strain to pull them out of the ferrule. The inner surfaces of the 50 wedges crowd the bristles over against the wedge-shaped point of the tongue, holding the bristles thus firmly in a mass, and giving to the flat ends of the bristles on each side of the middle line of the brush a tendency toward such line, or an inward thrust, whereby the bristles on one side support by their elasticity those on the other side when the brush is used, and the elasticity and wear of the 55 bristles are uniform.

I am aware that a brush has been devised the handle of which has a wedge which comes among the bristles in the ferrule. Such wedge is shaped the reverse of the one shown in my device, being larger at its lower end. 60

I am also aware that a brush has been devised which is provided with a ferrule made conical inside or flaring, and that the handle of the brush has a conical end which comes among the bristles in the ferrule. 65

Having thus described my invention, what I claim is—

The handle and cap provided with the wedge-pointed tongue and the mass of bristles, in combination with the ferrule and the 75 wedges E, the latter being placed within the sides of the ferrule at the bottom alongside of the bristles, with their thin edges next to the butts of the bristles, substantially as described.

JOHN FRANCIS BOWDITCH.
